UNITED STATES PATENT OFFICE.

OTTO J. KUENHOLD, OF CLEVELAND, OHIO.

REGULATOR FOR HOT-WATER HEATING SYSTEMS.

1,233,885.

Specification of Letters Patent.

Patented July 17, 1917.

Application filed December 13, 1913. Serial No. 806,368.

To all whom it may concern:

Be it known that I, OTTO J. KUENHOLD, citizen of the United States, residing at Cleveland, in the county of Cuyahoga and 5 State of Ohio, have invented certain new and useful Improvements in Regulators for Hot-Water Heating Systems, of which the following is a specification.

This invention relates to an automatic regulator for hot water heating systems, and the invention consists in the construction and combination of parts substantially as hereinafter shown and described and more particularly pointed out in the claims.

15 In the accompanying drawings the single figure shows a sectional elevation of the regulator.

The regulating device indicated as a whole by B is provided with such means internally 20 that the pressure of the water within the system in which the regulator is installed will be automatically regulated within certain predetermined limits, and the novel parts internally comprise two separate plungers 10 and 13 in parallel relation and working respectively in casings 10' and 13' which are integral portions of the main body B. The plunger 10 controls two valves 17 and 19, integral therewith and having seats 18 and 20 disposed relatively above and below the main water inlet or entrance 7, and both valves open downward under the action of plunger 10 and the spring 9 which bears on 30 said plunger from above. The said spring 9 is shown as confined in a tubular cap or extension 29 threaded upon the main portion of body above the plunger casing or portion 10'.

The plunger 13 has a valve 15 rigid there- 40 with and adapted to seat downward upon seat 21' in the casing 21. The top wall of body B connects the two casings or portions 10' and 21 therein and is provided with a duct 27 leading from one casing to the other for a purpose hereinafter described. A spiral spring 14 is seated on valve 15 in the casing and the extension 28 above the same, as shown, and which extension or cap corresponds to cap 29 and serves as a housing 45 for said spring and normally holds the valve 15 and its plunger 13 on their respective seats, the said plunger being seated at 23 within the casing 13'. A small orifice 24 enters said casing from the otherwise open 50 water space within the body B below plunger 13 and serves to take care of excess pres-

sure within said body as hereinafter fully described.

The water passes to the heater, not shown, through the bottom opening or outlet 11 in 60 the reducer connection 12 which is screwed into said body from beneath and is provided with a comparatively fine wire mesh screen 30 adapted to prevent the passage of objectionable particles into the regulating 65 device when expansion of water occurs and backs into the same. The enlarged threaded opening in the bottom of body B occupied by pipe connection 12 is large enough to permit the plunger 10 and its valves to be 70 removed and replaced through the same.

The opposed end surfaces of the two valves 17 and 19 are of the same area, and the opposed surfaces of the valve 17 and the plunger 10 also have the same area, so 75 that the pressure from the intake 7 is equal on both valves, and the pressure within the receptacle is also equal on the plunger and the upper end of valve 17. The opposed end surfaces of plunger 13 and valve 15 are also 80 of equal area to counterbalance the pressure from within the regulator. The said plungers and springs, furthermore, are so arranged and proportioned that the pressure of the water entering through inlet 7 is au- 85 tomatically regulated within certain predetermined limits, and the water pressure upon the lower enlarged end of valve 19 is counterbalanced by the pressure of spring 9. It follows that when the water pressure in the 90 system through opening 11 is less than the pressure of said spring the plunger 16 and its attached valves will be depressed from their seats and the water will enter the interior of body B from the service connection 7 95 until the system is fully supplied. When the back pressure of the water against the bottom of valve 19 exceeds the pressure of spring 9, the water inlet to the system will be automatically closed.

When the pressure in the system becomes abnormal, relief is afforded by the plunger 13 and valve 15, which have opposed surfaces of equal area alike exposed to the water in body B, and a further surface at the 105 bottom of the plunger is also exposed to the water pressure within the regulator. Plunger 13 is counterbalanced by spring 14, but when the water in the boiler is heated and begins to expand the water within the regulator will pass through the orifice or duct 110 24 to overcome the pressure of spring 14 and

the said plunger 13 will be slowly raised and valve 15 opened to permit the excess pressure to waste through exhaust 8. After sufficient relief the said valve and plunger 5 13 and 15 will again return to normal under pressure of spring 14 and the first condition be restored. The action is automatic and repeated indefinitely as the conditions arise. Obviously the motion of plunger 13 10 cannot be rapid as the orifice 24 is comparatively small, and otherwise the chamber or space in casing 13' beneath said plunger is closed. It will also be noticed that the exhaust passage 8 is of such size at its mouth 15 as to extend above valve 15, so that any slight leak past the valve will drain into the sewer and the transverse duct 27 in the top wall of the body B from above plunger 10 serves to drain therefrom into the sewer 20 in like manner. Set screws 36 over the springs 9 and 14 respectively serve to fix the tension of the springs so that any desired water pressure may be maintained in the system either higher or lower than the pressure in the water supply through inlet 7. For example, spring 9 may be placed under a tension requiring a pressure of say 30 25 pounds to close valve 19, and spring 14 may be set to permit valve 15 to open when a pressure of about forty pounds is reached.

The complete regulator is comparatively small and inexpensive, and dispenses the usual expansion tank and the lines of pipe thereto and therefrom, and also dispenses 30 with other devices commonly used in hot-water heating systems, such for example as the so-called heat generators. The regulator may also be located near the heater or boiler in the basement of a building or near 35 the service connection, and it prevents the hot water in the system from backing into the service pipes. The regulator is also entirely automatic in its operations, and requires no attention or care, and makes the 40 hot-water heating system safe and reliable as a whole. The occupant of the residence using this installation may also adjust the regulator at will to meet radically different 45 heating requirements, such adjustment being by the set screws to raise or lower the pressure in the system.

I claim:

1. A regulating device for hot water heating systems having a body with supply and 50 relief openings and a water supply regulating mechanism consisting of a pair of

valves and seats therefor relatively above and below the supply opening and a plunger controlling said valves having a casing about the same and open at its inner side to 60 the interior of said body and a spring bearing upon said plunger and adapted to depress said valves from their seats, in combination with a valve and a plunger connected therewith having equal areas exposed 65 to the water in said body and controlling said relief opening, a spring pressing upon said relief valve and plunger and a duct leading from the interior of said body into the chamber beneath said plunger. 70

2. A regulator for hot water heating systems having a hollow body with a supply opening at one side and valve seats relatively above and below said opening on its inside and a relief opening having a valve 75 seat, valves for said supply openings and a plunger connected with said valves and adapted to be depressed to open said supply openings, a tubular cap above said plunger and a spring in said cap bearing on said 80 plunger, in combination with a relief plunger and valve controlling the said relief passage, a tubular cup above said relief valve, a spring in said cup bearing on said valve, a duct leading from the interior of said body 85 to beneath said relief plunger and means leading from above said supply opening plunger to a point above said relief valve placing said cups in communication with each other. 90

3. A regulator for hot water heating systems having a hollow body with a supply opening at one side and valve seats relatively above and below said opening on its inside and a relief opening having a valve 95 seat, valves for said supply openings and a plunger connected with said valves and adapted to be depressed to open said supply openings and a spring bearing on said plunger, in combination with a relief plunger, plunger casing and valve controlling the said relief passage and a spring bearing on said plunger and adapted to close said valve and means placing said body portion in communication with said plunger casing. 100

In testimony whereof I affix my signature in presence of two witnesses.

OTTO J. KUENHOLD.
